UNITED STATES PATENT OFFICE.

FREDERICK L. THOMPSON, OF MEMPHIS, TENNESSEE.

COMBINATION DOUGH ROLLER AND CUTTER.

1,100,853.

Specification of Letters Patent. Patented June 23, 1914.

Application filed March 15, 1913. Serial No. 754,620.

To all whom it may concern:

Be it known that I, FREDERICK L. THOMPSON, a citizen of the United States, residing at Memphis, in the county of Shelby and State of Tennessee, have invented certain new and useful Improvements in Combination Dough Rollers and Cutters; and I do hereby declare the following to be a full, clear, and exact description of the invention, such as will enable others skilled in the art to which it appertains to make and use the same.

This invention comprehends improvements in dough rollers and cutters, and has for its primary object the provision of a very strong and simple device of this nature which will prove a very useful and convenient household article.

Another and more specific object of the invention is to provide a novelly formed wire structure for holding the roller and cutter, said structure permitting an easy detachment of the before mentioned members.

Another object of the invention is to provide a wire frame for holding a cutter and roller and a spiral locking member for holding the cutter and roller within said frame.

The invention also aims to generally improve devices of this nature to render them more practical and commercially desirable.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a top plan view of my combination roller and cutter, Fig. 2 is a side elevation with the handle broken away, and, Fig. 3 is a detail fragmentary view taken on the plane of line 3—3 of Fig. 2.

Referring in detail to the drawings by characters of reference, A designates a cylindrical roller formed preferably of wood and having sockets 5 provided in the ends thereof.

B designates, generally, a frusto-conical cutter, which, if desired, may be strengthened by any suitable means, not shown, and which is provided upon its exterior surface at diametrically opposite points, with the sockets 6. As shown in Fig. 3, the sockets

are rectangular in cross-section for a purpose to be hereinafter described.

To connect and support the roller A and cutter B, I provide a frame C and for the purpose of actuating the entire device, I provide a handle D.

To form the frame and handle I employ a continuous metallic rod which is bent centrally of its ends so as to form the handle portions 7 and 8. The rod is then extended angularly from the inner ends of the handle portions 7 and 8, as shown at 9, then bent outwardly, as indicated at 10. To form the frame C, the strands of the rod are extended upwardly from the outer ends of the sections 10 to form the upright frame bars 11, then extended angularly and bent back upon themselves to provide the projections 12. The end portions of the rod form the arched frame bars 13, which have their free extremities inturned, as indicated at 14, for the purpose of projecting into the sockets 5 in the roller A. It will be noted that the handle D and the rod sections 9 and 10 are disposed in a plane which extends at right angles to the plane of the frame C.

To draw the projections 12 toward one another so as to support the cutter B, I provide a spiral clamping member E, which is permanently attached to the section 8 of the handle by being looped into engagement therewith, as indicated at 15. The clamping member is formed of a continuous metallic rod bent so as to form a spiral shaped opening 16 for the reception of the other handle section 7.

Referring to Fig. 2, it will be seen that by turning the clamping member in a counter-clockwise direction, the handle sections will be drawn together, which will cause a similar movement of the projections 12, which support the cutter. By turning the clamping member sufficiently far, the handle section 7 will become wedged between the walls at the inner end of the opening 16 and therefore the frame projections 12 will be securely locked against outward movement.

The walls of the rectangular sockets 16 closely engage the portions of the metallic rod which form the projections 12 and therefore the cutter is held against rotational movement when said projections are forced inwardly. When it is desired to reverse the cutter so as to bring its opposite end into operative position, it is necessary to first turn the clamping member E so as to permit

the handle sections to separate, and after this has been done the frame may be easily sprung so as to withdraw the projections 12 from the sockets 6. Since the rod which forms the frame and handle is somewhat resilient, these will normally assume the position shown by the dotted lines in Fig. 2.

From the foregoing description taken in connection with the accompanying drawing, 10 it will be seen that I have provided an extremely simple and practical combination device, which may be used for rolling dough and for cutting the same into pieces of various sizes.

15 It is to be understood that while I have shown and described the preferred embodiment of my invention, I do not wish to be limited to this exact construction, combination, and arrangement of parts, but may 20 make such changes as will fall within the spirit and scope of the invention.

Having thus described my invention, what I claim is:—

25 1. A device of the character described, comprising in combination, a roller having sockets formed in the ends thereof, a cutter having sockets secured to the exterior thereof, a frame including side bars having their free ends inturned for reception within the 30 sockets formed in the end of said roller, the other ends of said side bars being bent back upon themselves to provide supporting projections adapted to fit within the sockets

carried by the cutter, a handle extending laterally from said frame and comprising 35 two sections, the handle and frame being formed of a continuous rod, and means for drawing the handle sections together, whereby the cutter and roller will be securedly 40 fixed within the frame.

2. In a device of the character described, the combination with a supporting frame and handle formed of a continuous metallic rod, the frame including side bars and the handle including essentially parallel sections, of a spiral clamping member fixed to one of said handle sections and adapted to engage the other of said handle sections, whereby the side bars of the frame may be drawn toward one another. 50

3. A device of the character described including a frame, a roller journaled in said frame, a reversible cutter, sockets carried by said cutter, the frame being formed with projections adapted to fit in said sockets, the 55 projections being adapted to spring from said sockets to permit of the cutter being reversed, and means for locking the projections within the sockets whereby the cutter and frame are rigidly connected. 60

In testimony whereof I affix my signature in presence of two witnesses.

FRED. L. THOMPSON.
